UNITED STATES PATENT OFFICE.

WILLIAM M. WATTS, OF GREEN COVE SPRINGS, FLORIDA.

AXLE.

1,183,927.

Specification of Letters Patent. Patented May 23, 1916.

Application filed March 9, 1914. Serial No. 823,423.

To all whom it may concern:

Be it known that I, WILLIAM M. WATTS, a citizen of the United States, residing at Green Cove Springs, in the county of Clay,

5 State of Florida, have invented certain new and useful Improvements in Axles; and I do hereby declare the following to be a full, clear, and exact description of the invention, such as will enable others skilled in the art 10 to which it appertains to make and use the same.

The present invention is directed to improvements in axles, and has for its object to construct devices of this character in such a 15 manner that the spindles may be readily removed when worn and replaced with perfect ones. With this and other objects in view, this invention resides in the novel features of construction, formation, combination, 20 and arrangement of parts to be herein-after more fully described, claimed and illustrated in the accompanying drawing, in which:

Figure 1 is an end view of the axle; Fig. 25 2, is a side view of a portion of the axle, and Fig. 3, a sectional view on the line 3—3 of Fig. 2.

In the drawings 11 indicates the axle which is I-shaped in cross section. A recess 12 is 20 provided in the end of the axle for receiving the web 13 of the section 14, said section hav-

ing its outer end provided with a circular head 15 which latter is provided with grooves 16 and 17 intersecting at their centers so as to receive ribs 18 formed upon the circular 35 head 19 of a spindle 20. Bolts 21 are passed through the heads 15 and 19 so that they may be readily disconnected should the spindle become worn or broken. Bolts 22 are engaged through the section 14 and the axle 40 11 on either side of the recess 12 to secure said section to the axle.

What is claimed, is:—

In combination with an axle end formed of an I-beam the end portion of the web of 45 which is provided with a longitudinal recess opening through its end, a section having an I-shape cross section the web of which is detachably engaged in the recess with its flanges disposed between the flanges 50 of the axle end, securing members extending through the flanges of the section and the web of the axle end section and the web of the axle end, and a spindle secured to each section. 55

In testimony whereof, I affix my signature, in the presence of two signatures.

WILLIAM M. WATTS.
